SURF BOARD

William T. Currey, Galveston, Tex.

Application February 5, 1935, Serial No. 5,119

1 Claim. (Cl. 9—11)

This invention relates to that class of devices which are intended to support one or more persons when towed behind a swiftly moving craft such as a motor-boat or the like and which are commonly known as "surf boards" although I preferably term the present invention as a "sea scooter" as a convenient appellation to distinguish its character.

Ordinarily such surf boards have been constructed of wood with, in some forms, having their front ends upwardly curved somewhat thus resembling a toboggan. Devices thus constructed are generally lacking in sufficient buoyancy to support the weight of the user unless the device is pulled rapidly through, or rather over the surface of the water.

These wooden devices are subject to, not only flotation defects but are, because of their rigidity, productive of unpleasant shocks to the legs of the riders.

Furthermore, in the construction of such devices of wood or the like they cannot be readily collapsed to occupy small space for transportation.

One important object of the present invention is to provide a device of this character which will have, when in use, ample floatative power to support the user or users even when quiescent.

A second important object of the present invention is to provide a novel form of a device of this character having such inherent flexibility as to prevent undesirable shocks to the rider or riders as the device is towed over the ripples and waves commonly present where such devices are used.

A third important object of the present invention is to provide a novel form of device of this character which may be collapsed or inflated as desired, the device when collapsed occupying a relatively small space while, when inflated, is highly superior to the usual wooden surf board.

With the above and other objects in view, as will be understood from what follows, the invention consists in general of certain novel details of construction and combinations of parts hereinafter fully described, illustrated in the accompanying drawing and specifically claimed.

In the accompanying drawing like characters of reference indicate like parts in the several views, and:

Figure 1 is a perspective view of the complete device inflated and ready for use,

Figure 2 is a section on the plane of the line 2—2 of Figure 1,

Figure 3 is a section on the plane of the line 3—3 of Figure 1,

Figure 4 is a perspective view of the rear end of the device in its opened condition, and

Figure 5 is a section on the plane of the line 5—5 of Figure 1.

In the form of the invention shown in the present drawing there is provided an outer casing including a spaced pair of fabric side members 10 of straight formation along the greater 10 portion of their length, their forward ends being upturned as at 11 and having rounded forward edges 12.

These strips 10 are provided with out-turned flanges 13 at their upper, lower and forward edges 15 and a wrapper sheet 14 extends from the upper rear end of the sides 10 forwardly over and around the upturned portions to extend rearwardly in contact with the lower flanges 13 back to the rear ends of the side strips 10. This wrapper sheet 20 is secured to the flanges 13 by stitching 15 (see especially Figure 4). The wrapper sheet 14 has rearwardly extending flaps 16 of such extent as to close the rear end of the casing formed by the sides 10 and wrapper 14 and these 25 extensions 16 are provided with eyelet holes 17 through which a lacing 18 passes to effect proximation of the flaps 16 so as to properly close the rear of the casing. Now, from what is shown in the drawing and has been described 30 in the specifications, it will be seen that there has been provided a shallow and box-like construction having an upturned forward end and access means at its rear end which may, at will, be closed.

Extending longitudinally through the hollow casing thus formed are parallel tubes 19 of rubber or other expandable material so proportioned that when fully expanded they will fill, as shown at 19', practically all the space within the casing. 40 However, in order to afford lateral rigidity to the device and to prevent the tubes from being displaced from their proper positions there is provided a series of transverse brace members 20 stitched to the top and bottom parts of the 45 wrapper sheet so as to hold the said top and bottom portions of the wrapper sheet in evenly spaced relation. These transverse braces are secured to the top and bottom portions of the 50 wrapper sheet by stitching 21 extending through said wrapper sheet and flanges 22 on said members 20. These members 20 are perforated to permit the passage of the tubes 19, the tubes being expanded between the members 20 as at 55

19'. Each tube has at its rear end a filling valve 23 wherethrough it may be inflated.

Spaced tabs 24 are provided on the upper and lower portions of the wrapper 14 at their rear edges which tabs are connected together by lacing 25. Extending from the rear end of each side member 10 is a side flap 25', these flaps being of such length that one overlaps the other when they are closed over the rear end of the casing and each flap is provided with eyelet holes 26 to receive the filling stems or nipples 23. A protecting flap 27 is secured beneath one of the flaps 16 to one rear end of the wrapper sheet 14 and covers the outer ends of the nipples 23. The rear end of each tube 19 is reinforced by a boot 28 of relatively rigid material.

In use the tubes 19 are inflated by supplying them with air from a suitable source as, for instance, a tire pump or with air from a pressure tank. The valves 23 are then capped in the usual manner, the flaps 25' folded over, the tabs 24 laced together, the flap 27 folded to rest against the valve caps, and the flaps 16 laced together. For transportation, the rear of the device is opened at its rear end, and the tubes deflated by permitting the air to escape through their valves, in the usual manner.

There has thus been provided a highly efficient and improved device of the kind described and for the purpose specified. It is obvious that changes may be made in the form and detail construction of the invention as illustrated herein and particularly described. Therefore, it is not desired to limit the invention to such specific form but it is desired to include all such devices as come within the scope of the appended claim. 10

5 What is claimed is:

A device of the kind described including a casing having top, bottom, and side walls and an open end, inflatable members within the casing each having a filling nipple connected thereto, 15 side flaps connected to the side walls and adapted to overlie the inflatable members, said flaps having openings to receive the nipples therethrough, tabs connected to opposite walls of the casing and adapted to overlie the side flaps, 20 means for connecting the tabs together, a protecting flap secured to the casing and adapted to overlie the nipples, closure flaps secured to the casing and adapted to overlie the protecting flap, and means for securing the closure flaps together. 25

WILLIAM T. CURREY.
